Primary Examiner — Garth Rademaker*Assistant Examiner* — Aaron C Fowler(74) *Attorney, Agent, or Firm* — Banner & Witcoff, Ltd.(57) **CLAIM**

The ornamental design for a stroller as shown and described.

DESCRIPTION

FIG. 1 is a front view of a stroller showing our new design;
FIG. 2 is a rear view thereof;

FIG. 3 is a side view thereof;

FIG. 4 is a top view thereof;

FIG. 5 is a bottom view thereof;

FIG. 6 is a front perspective view thereof;

FIG. 7 is a rear perspective view thereof; and,

FIG. 8 is an opposite side view thereof.

The broken lines depicting the remainder of the stroller form no part of the claimed design.

1 Claim, 8 Drawing Sheets(56)
